(57) **CLAIM**

The ornamental design for a beverage dispenser, as shown and described.

DESCRIPTION

FIG. 1 is a front left perspective view of a beverage dispenser showing our new design;

FIG. 2 is a front right perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof; and,

FIG. 8 is a bottom plan view thereof.

The even length dashed broken lines are for environmental purposes only and form no part of the claimed design.

The uneven length dot-dash broken lines represent an unclaimed boundary line and form no part of the claimed design.
